UNITED STATES PATENT OFFICE.

LUCIAN F. EASTON, OF LA CROSSE, WISCONSIN.

TEMPERATURE-CONTROLLING APPARATUS FOR INTERNAL-COMBUSTION ENGINES.

Application filed January 9, 1922, Serial No. 527,804. Renewed December 3, 1924.

The present invention relates to controlling devices adapted to be associated with internal combustion engines.

In controlling systems associated with internal combustion engines, in which an actuator, that is operative by vacuum effect, is employed, it sometimes occurs that the available vacuum-producing means is insufficient for efficient operation of the actuator, and the invention relates to controlling devices which are operable by an internal combustion engine, for example, such as the controlling-devices for the circulation of cooling air through the radiator for the cooling liquid for the motor.

In some of the temperature controlling systems of the prior art, a vent, thermostatically controlled in accordance with the temperature of the engine, is connected with a vacuum line connecting the intake manifold with a shutter actuator in the form of a suction controlled device, such as bellows or a diaphragm operatively connected with the shutter of the radiator to be controlled. In these systems, the shutters are closed when the engine is at rest or is cold, the thermostat keeping the vent open to destroy the vacuum effect in the motor, but when the engine becomes heated to a certain degree, the thermostat causes the shutters to be opened. When the engine is stopped, the vacuum in the intake manifold is destroyed, due to its connection with the outer air to the carburetor, and the shutters will close regardless of the temperature. These systems, however, have objections, for example, when the engine is on full throttle with no restriction to the entrance of air through the carburetor except the friction, there is a very low vacuum in the intake manifold, the result being that there is very little power for moving the shutters unless a very large actuator is used.

The object of my invention is to overcome the objections in controlling systems, and this is attained by means of an aspirator, through which air, gas, oil or other fluid is forced under velocity and which is connected with the actuator. The vacuum producing flow through the aspirator may be produced by any suitable fluid, for example, the fluid under suction in the engine mani-

fold or the fluid in the exhaust manifold, or it may be connected with both of said manifolds. By using such an aspirator, the vacuum effect in the actuator can be increased over the vacuum in the manifold from about thirty per cent, when the vacuum is high in the manifold, to about three hundred to four hundred per cent when it is low in the manifold. With the aspirator, the shutters or other device will be held open under practically all operating conditions, even with the manifold vacuum practically at zero, as indicated on ordinary vacuum gauge. In fact, the use of the aspirator will make practical the impractical and inefficient vacuum systems which have been heretofore used.

In the accompanying drawings: Fig. 1 is a side elevational view of the front end of an automobile, showing the engine structure and radiator structure, with controlling mechanism embodying the invention. Fig. 2 is an enlarged side elevation of the aspirator and its operating connection with the manifolds of the engine. Fig. 3 is an enlarged vertical section through the radiator structure. Fig. 4 is a section taken on line 4-4 of Fig. 3, and Fig. 5 is a section taken on line 5-5 of Fig. 4.

The invention is exemplified with an internal combustion engine provided with an intake manifold 10 for the combustible fluid delivered to the engine-cylinders, an exhaust manifold 11 for the products of combustion, a radiator, consisting of a grill R and upper and lower tanks R' which are suitably connected by an upper hose connection 13 and the usual lower connection (not shown) to the usual water-jacket around the engine-cylinders for the circulation of cooling water, and a fan 12 of usual construction for forcing air through the radiator grill. In front of the radiator and suitably secured thereto is a rectangular frame 14 across whose opening 15 extend, in vertical series, the shutters 16 which are pivoted by means of pins 17 to the side-walls of said frame. These shutters have rearwardly extending wings 18, each connected at 19 with a bar 20, which is shiftable vertically to conjointly close or open the shutter. This bar is normally held raised to keep the shutters closed by a suitably applied spring or, as

shown, by a weight 21 on an arm 22 extending forwardly from one of the shutters below its pivot point. The weight will yieldingly hold one shutter in vertical position and thereby hold the bar 20 raised so that all the other vanes will likewise be in vertical and closed position, as shown in full lines in Fig. 3.

The actuating device for the shutter mechanism is exemplified by expansible bellows 23 which extend from a wall 24 which is adjustably supported by rods 25 on the vertical wall 26 of a bracket 27 secured to the upper radiator tank R' at the rear side thereof. The movable wall 28 of the bellows is connected by rods 29 with a yoke 30, the rods extending through guideways 31 in the wall 26.

Yoke 30 is connected by a rod 32 with the outer arm of a bell-crank lever 33 which is pivoted, at 34, on the frame 14, the other arm of the lever being pivoted to the upper end of the shutter actuating bar 20. When the pressure in the bellows 23 is normal, that is, at atmospheric pressure, the force of the weight 21, which closes the shutter, will also, through the medium of the bell-crank lever 33 and the rod 32, pull the bellows open to expanded position. When the pressure within the bellows is now reduced, it will contract and exert pull on the rod 32 and rotation of the bell-crank lever 33, to force the bar 20 downwardly to open the shutters.

The suction or vacuum effect within the bellows is obtained by means of an aspirator A. This device comprises a fitting with a horizontal member 35 and a vertical member 36. Through member 35 extends the flared bore 37 with which communicates the bore 38 in member 36. Member 35 has the threaded necks 39 and 39' for receiving the coupling nuts 40 and 41 respectively, while member 36 has the reduced threaded neck 42 for receiving the coupling nut 43. One end of member 35 is connected with the intake manifold 10 of the engine by a pipe 44 which leads from said manifold and is coupled to the aspirator by nut 41. Pipe 45 is coupled to the lower end of member 36 of the aspirator by nut 43 so that the duct 38 of the aspirator will be in constant communication with the bellows 23. Interposed in the pipe 45 is a fitting 46 (Fig. 1) which is connected by the pipe 47 with the fitting 48 which extends into the chamber 49 formed in the housing 50 which contains a suitable thermostat 51. Housing 50 is provided with suitable openings (not shown) so that chamber 49 will be opened to atmosphere. This thermostat may be of the ordinary construction comprising the bars 52 and 53 of different co-efficients of expansion, and secured together throughout their lengths and anchored at their lower ends to the frame

50 by the block 54. Fitting 48 has a duct 55 which terminates at a valve-seat 56, with which the plate 57 on the thermostat is adapted to co-operate to either open or close said duct. A set screw 54' is provided for adjusting the plate 57 with reference to the valve seat. The housing 50 is applied to receive the heat of the cooling water in the radiator. As shown, it is secured against the inner side of the upper tank R', so that the chamber 49 will always be of substantially the same temperature as the cooling water. The thermostat could, of course, be applied against the engine frame, but as the water passing through the radiator is usually of the same temperature as the engine, this tank R' affords a convenient place for supporting the thermostat.

As already explained, one end of the body of the aspirator is connected with the intake manifold. The other end of the body may be connected with atmosphere or with the exhaust manifold. As shown on Figs. 1 and 2, a pipe 58 is coupled to the aspirator by means of coupling 40. This pipe connects with a valve 59 which is connected by pipe 60 with the exhaust manifold 11. The plug 61 of valve 59 has a passageway 62 which, in one position, will connect the aspirator with the pipe 60 and the exhaust manifold, and which, in another position will disconnect the exhaust pipe and connect the aspirator with the passageway 62 connected with the atmosphere. When the valve plug is turned to an intermediate position, both the atmosphere and the exhaust pipe will be disconnected from the aspirator.

In operation, when the engine is at rest and is cold, the thermostat is swung away from the valve-seat 56 to expose the duct 55 to atmosphere and thus destroy any vacuum effect in the pipe 45 connected with the bellows. The bellows is then expanded, as shown in Fig. 4, and the weight 21 holds the shutters closed. When the engine is started, the vacuum effect in the intake manifold will be communicated to the aspirator A, but the pipe 45 is then vented to atmosphere at the fitting 48, so the shutters will remain closed until the temperature of the water rises sufficiently to cause the thermostat element to engage the valve seat 56 and close the air vent. If the valve 59 is set to connect the aspirator with atmosphere, then the suction in the intake manifold causes air to flow at great velocity through the tapered duct 37 past the end of the duct 38, which is connected with the pipe 45, and suction effect will be caused in the bellows and the latter will contract to exert pull on the rod 32 and swing of the bell-crank lever 33 to push down the bar 20 and to open the shutters. When the shutters are opened, the air circulates through the radiator grill and cools the water and, as soon as the tem-

perature drops sufficiently, the thermostat will reopen the vent and destroy the suction in the bellows and the weight 21 will then restore the shutters to closed position. It is very important that the vent passageway through fitting 48 be less restricted to atmosphere flow than the bore 38 of the aspirator, so that when the thermostat opens the vent passageway to atmosphere, all suction effect in the bellows is destroyed.

As the carburetor throttle valve is opened more and more and the power of the engine increases, the vacuum in the intake manifold decreases, and if the manifold were connected directly with the bellows, it might be impossible to keep the shutters open. By interposing the aspirator, the decrease in vacuum is compensated for by the velocity of the air flowing through the duct 37. The suction pull on the bellows, instead of being decreased, is therefore considerably increased as the power of the engine increases and the shutters are held open with considerable power. In practice, it has been found that the aspirator will produce at least thirty per cent more vacuum effect in the actuator, when the vacuum force in the intake manifold is at a maximum, and when the vacuum force within the manifold is at a minimum, the aspirator will produce from three hundred per cent to four hundred per cent greater vacuum effect in said device than would be the case if the manifold were directly connected with the motor. By using the aspirator, a comparatively small actuating motor will suffice to positively and powerfully control the shutters. The leverage of the weight action on the shutters decreases as the shutters are opened, so that less power is required to hold the shutters in open position than to start them from closed position toward open position.

By connecting the aspirator with the exhaust manifold, instead of to atmosphere, which may be done by setting valve-plug 61 to establish communication between the aspirator and said manifold, the exhaust pressure added to the suction pull of the intake manifold will increase the vacuum effect at the shutter actuating device. The exhaust gases blowing into the intake manifold will also assist in vaporizing the fuel, and this is of particular advantage when starting a cold engine, as the heated explosive mixture will cause the engine to start more rapidly than if a cold mixture were delivered.

When the valve 61 is turned to an intermediate position, both the exhaust and atmosphere will be disconnected from the aspirator and the vacuum effect of the intake manifold will be communicated directly to the bellows or other vacuum controlled motor. Under some conditions, it may be desirable to use this arrangement.

The invention exemplifies a controlling

system that is adapted to be operated in connection with internal combustion engines and in which the actuator is operated by vacuum effect produced by an aspiration. While the actuator has been illustrated and described as operating a radiator shutter, it will be understood that it may be used to operate other devices.

The invention is not to be understood as restricted to the details set forth, since these may be modified within the scope of the appended claims, without departing from the spirit and scope of the invention.

Having thus described the invention, what I claim as new and desire to secure by Letters Patent, is:—

1. The combination with an internal combustion engine, of a controlling device operable by fluid, and means for operating said device comprising a jet connected to exhaust fluid from the device by aspiration.

2. The combination with an internal combustion engine, of a controlling device operable by fluid, means for operating said device comprising a jet connected to exhaust fluid from the device by aspiration, and a connection for operating the jet by suction produced by the engine.

3. The combination with an internal combustion engine, of a controlling device, an actuator for said device operable by fluid, means for operating said actuator comprising a jet connected to exhaust fluid from the actuator by aspiration, and a connection for operating the jet by suction produced in the engine.

4. The combination with an internal combustion engine, of a fluid-operable controlling device, and means effective during the running of the engine, for operating said device comprising a jet connected to said device to exhaust fluid therefrom by aspiration and connected to the engine.

5. The combination with an internal combustion engine, of a controlling device, a fluid-operable actuator for said device, and means effective during the running of the engine for operating said actuator comprising a jet connected to exhaust fluid from the actuator by aspiration and connected to be operated by suction produced by the engine.

6. The combination with an internal combustion engine and a cooling system for said engine, of means for controlling the cooling system, and means effective during the running of the engine for operating said controlling means comprising an aspirator connected to said controlling means and provided with a jet for exhausting fluid therefrom by aspiration.

7. The combination with an internal combustion engine and a cooling system therefor, of controlling means for said system comprising a thermostat, pressure controlled means effective during the running of the

engine and controlled by said thermostat, and an aspirator connected to the engine and to said pressure controlled means provided with a jet for exhausting fluid by aspiration.

8. The combination with an internal combustion engine and a water cooling system therefor including a radiator, of means for controlling the flow of air through said radiator, pressure-controlled means for actuating said air flow controlling means, an aspirator connected with said actuating means and provided with a jet for exhausting fluid by aspiration, and means effective during running of said engine for operating said aspirator to change the pressure condition at said actuating means to cause actuation of said air flow controlling means.

9. The combination with an internal combustion engine and a water cooling system therefor including a radiator, of means for controlling the flow of air through said radiator, pressure controlled means for actuating said air flow controlling mechanism, an aspirator connected with said actuating means and provided with a jet for exhausting fluid by aspiration, means effective during operation of the engine for operating said aspirator, and means controlled by the temperature of the cooling system for controlling the effect of said aspirator on said actuating means.

10. The combination with an internal combustion engine and a water cooling system therefor including a radiator, of means for controlling the flow of air through said radiator, an aspirator having a jet for exhausting fluid by aspiration, means controlled during the running of the engine for creating a suction producing stream through said jet, a pressure controlled actuating device for said air-controlling mechanism connected with said aspirator to be subjected to the suction effect created thereby, the operation of said device by said suction effect causing said air flow controlling means to permit flow of air through the radiator, and means controlled by the temperature of the cooling system for determining the application of the aspirator suction effect on said actuating device.

11. The combination with an internal combustion engine and a water cooling system therefor including a radiator, of means for controlling the flow of air through said radiator, an actuating device for said air flow controlling mechanism responsive to suction, an aspirator having a jet for exhausting fluid by aspiration, means controlled during running of the engine for creating a suction producing stream through said jet, said actuating device being connected with said aspirator to be subjected to the suction effect created thereby, and thermostat means subjected to the tempera-

ture of the cooling system for controlling the effectiveness of the aspirator suction on said actuating device.

12. The combination with an internal combustion engine and a water cooling system therefor including a radiator, of mechanism for controlling the flow of air through said radiator, means tending to hold said mechanism closed, an actuator for said mechanism responsive to suction to open said mechanism, an aspirator having a jet for exhausting fluid by aspiration, means controlled during running of the engine for creating a suction producing stream through said jet, said actuator being connected with said aspirator and the suction created thereby, and means automatically controlled by the temperature of the cooling system for determining the effectiveness of the aspirator suction at said actuator.

13. The combination with an internal combustion engine and a water cooling system therefor including a radiator, of mechanism for controlling the flow of air through said radiator, said mechanism being closed when the temperature of the cooling system is below a certain point, an actuator connected with said mechanism and responsive to suction to open said mechanism for the flow of air through the radiator, an aspirator having a jet for exhausting fluid by aspiration, means controlled during running of the engine for creating a suction producing stream through said jet, a suction line connected between said aspirator and said actuator, an atmosphere vent for said suction line, and thermostat means subjected to the temperature of said cooling system, said thermostat device being associated with said vent to open said vent when the temperature is below a certain point to thereby prevent operation of said actuator and to close said vent when the temperature reaches a certain point to thereby permit said actuator to respond to suction to open said air flow controlling mechanism.

14. The combination with an internal combustion engine and a water cooling system therefor including a radiator, of mechanism for controlling the flow of air through said radiator, an actuator connected with said mechanism and operative by suction to open said mechanism, an aspirator connected with said actuator and having a jet for exhausting fluid by aspiration, and a connection between said aspirator and the engine intake manifold for causing suction producing flow through said jet when the engine is running.

15. The combination with an internal combustion engine and a water cooling system therefor including a radiator, of mechanism for controlling the flow of air through said radiator, an actuator connected with said mechanism and operative by suction

to open said mechanism, an aspirator connected with said actuator and having a jet for exhausting fluid by aspiration, a connection between said aspirator and the engine intake manifold for causing suction producing flow through said jet when the engine is running, and thermostat mechanism for preventing operation of said actuator until the temperature of the engine reaches a certain point.

16. The combination with an internal combustion engine and a water cooling system therefor including a radiator, mechanism for controlling the flow of air through said radiator, means tending to close said mechanism, an actuator connected with and responsive to suction to open said mechanism, an aspirator and having a jet for exhausting fluid by aspiration, a connection between said aspirator and the intake manifold of said engine for causing a suction producing stream through said jet, a suction line between said aspirator and said actuator having an atmosphere vent, and a thermostat for controlling said vent in accordance with the temperature of said engine.

17. The combination with an internal combustion engine and a water cooling system therefor including a radiator, mechanism for controlling the flow of air through said radiator, means tending to close said mechanism, an actuator connected with and responsive to suction to open said mechanism, an aspirator having a jet for exhausting fluid by aspiration connected with the intake manifold of the engine whereby a suction creating stream is caused therethrough when the engine is running, said actuator being connected with said aspirator to be subjected to the produced suction effect, and means for connecting the exhaust manifold of said engine with said aspirator whereby warm gas will be drawn into the manifold to facilitate starting of the engine.

18. The combination with an internal combustion engine and a water cooling system therefor including a radiator, of mechanism for controlling the flow of air through said radiator, an actuator for said mechanism responsive to suction, an aspirator, means connecting said aspirator with the engine intake manifold whereby a suction producing stream will be caused through the aspirator when the engine is running, said actuator being connected with the aspirator to be subjected to the created suction effect, and means for connecting the intake end of said aspirator either with atmosphere or with the exhaust manifold of the engine.

19. The combination with an internal combustion engine and a water cooling system therefor including a radiator, of mechanism for controlling the flow of air through said radiator, means tending to close said mechanism, an actuator connected with and re-

sponsive to suction for opening said mechanism, an aspirator having a jet for exhausting fluid by aspiration connected with said engine to be operated to produce suction, said actuator being connected with said aspirator to be subjected to the created suction, and thermostat means subjected to the temperature of the engine for controlling the application of suction to said actuator.

20. The combination with an internal combustion engine, of a fluid operable controlling device, and means connected to the suction produced in the engine for increasing the suction, and connected to operate said device.

21. The combination with an internal combustion engine and a cooling system thereof, of fluid operable means for controlling the cooling capacity of the system, and means connected to the suction produced in the engine cylinder for increasing the suction, and connected to operate said device.

22. The combination with an internal combustion engine, and a cooling system therefor, including a radiator, of means for controlling the cooling capacity of the radiator, and an aspirator jet connected to the suction produced in the engine cylinder for increasing the suction, connected to operate said controlling means.

23. The combination with an internal combustion engine, of a fluid operable controlling device, thermostatic means for rendering the device operable by fluid, a jet connected to the suction produced in the engine cylinder for increasing the suction, and a connection between the jet and said device through which the increased suction will be applied to operate said device.

24. The combination of an internal combustion engine and a cooling system therefor, means for controlling the cooling capacity of the system, and means responsive to suction produced in the engine cylinders for actuating the controlling means comprising an element therein adapted to increase the power of the actuating means above the power of the suction produced in the cylinders themselves.

25. The combination with an internal combustion engine, of a controlling device operable by the suction of the engine, and a connection between the engine and the controlling device for operating the same by suction comprising an element therein for increasing the effective power of the suction upon the controlling mechanism above the powers of the suction in the engine itself.

26. The combination with an internal combustion engine and a cooling system therefor including a radiator, of means for controlling the cooling capacity of the radiator, a fluid operated actuator for said controlling means, a device for producing suc-

tion, a connection between the actuator and said device, and means for operating the suction producing means.

27. The combination with an internal combustion engine, of a controlling device operable by the suction of the engine, and a connection between the engine and the controlling device for operating the controlling device by suction comprising an element

therein operable by the suction of the engine 10 whereby the suction in the connection beyond the element is greater than the suction in the engine.

In witness whereof, I hereunto subscribe my name this 20th day of October A. D., 15 1921.

LUCIAN F. EASTON.
